UNITED STATES PATENT OFFICE

2,513,934

ELECTRIC SWITCH

Chester I. Hall, Vischer's Ferry, N. Y., assignor to
 General Electric Company, a corporation of
 New York

Application October 22, 1945, Serial No. 623,650

3 Claims. (Cl. 200—87)

1

My invention relates to electric switches, more particularly to electromagnetically operated switches of the type known as contactors, and has for its object a simple and reliable shock-proof electromagnetic operating means.

In carrying out my invention in one form I operate the movable switch contact by means of a plunger armature having a rack on one end which engages a pinion. The pinion is connected to a crank which, in turn, is connected by means of a link to a switch operating lever. I also provide a second rack mounted for slidable movement in a direction parallel with the movement of the first rack and engaging the pinion on a side opposite the first rack. This second rack is constructed to have a weight equal to the weight of the first rack and the armature combined so that the second rack acts as a counterbalancing weight, thereby making the armature and first rack free from shocks. Moreover, the mechanism is so arranged that the crank is moved from one dead center to another upon movement of the plunger, whereby the operating lever is secured in each position against the effect of shocks.

For a more complete understanding of my invention, reference should be had to the accompanying drawing, Fig. 1 of which is a side elevation view, partly in section, of a contractor embodying my invention shown in its open position; Fig. 2 is a front elevation view, partly in section, of the device shown in Fig. 1; Fig. 3 is a sectional view along the line 3—3 of Fig. 1 looking in the direction of the arrows, while Fig. 4 is a fragmentary view of the operating mechanism showing the parts in their contactor closed positions.

Referring to the drawing, I have shown my invention in one form as comprising an electrically insulating support 1 on which are mounted two spaced apart stationary contacts 2 and 3 with which cooperates a movable bridging contact member 4 mounted on an operating lever 5 having a stationary pivot 6. The lever 5 is mounted on a U-shaped, or channel-shaped, metal supporting member 7 having its base wall secured to the panel support 1. Likewise, the lever 5 is U-shaped, or channel-shaped, as shown clearly in Fig. 3, with its side flanges fitting loosely between the sides of the support 7 and pivoted thereto by a pivot 6 on each side.

Mounted between the side flanges of the support 7 at its upper end is a magnet frame 8 provided with an operating coil 9 and with a plunger armature 10 arranged for movement in

2

a substantially vertical direction. On the lower end of the armature 10 is secured a rack 11 extending longitudinally of the armature, the upper end of the rack being secured on a pivot 12 between the two projections of the forked lower end of the armature.

For operation of the lever 5, the rack 11 meshes with a pinion or gear 13 secured on a shaft 14 mounted at its ends on bearings 15 and 16 secured to the sides of the support 7, the shaft 14 extending parallel with the panel 1 and at right angles to the direction of movement of the armature 10. A second shaft 17 parallel with the shaft 14 is provided on the opposite side of the rack 11, this shaft being provided with a guide roller 18 engaging the opposite straight side of the rack 11 so as to hold the rack in meshing relation with the pinion. Also secured to the shaft 14 is a crank 19 having a crank pin 20 which is connected by a link 21 to a pivot pin 22 on the lever 5.

The operating parts are so arranged that when the plunger is in its lowermost unattracted position, as shown in Figs. 1 and 2, in which it rests 25 against a suitable stop (not shown), the crank pin 20 is in a substantially dead center position with respect to the pin 22. In other words, the centers of the two pins and of the shaft 14 lie substantially on a straight line. When the plunger is moved upward, upon energization of the coil 9, to its attracted position against a suitable stop (not shown) the crank 19 is turned substantially through a 180 degree angle substantially to its opposite dead center position, as shown in Fig. 4. Therefore, in each of its positions the crank holds the operating lever 5 securely whereby the operating lever is free from the effects of shocks. Preferably, however, for maximum shockproofness the crank is turned 35 through an angle somewhat greater than 180°, for example 190°, so that the crank is turned slightly beyond its dead center position in each direction.

I have also provided a second and weighted 40 rack 23 engaging the pinion 13 on its side opposite the rack 11 for the purpose of counterbalancing the weight of the plunger 10 and the rack 11, thereby to render the plunger 10 and rack 11 free from the effects of shocks applied 45 to the device. This counterbalancing rack 23 is secured to and includes a weight bar portion 24 which is mounted in guides 25 and 26 secured to the back wall or base of the support 7. By means of these guides the rack 23 including the 50 bar 24 is mounted for straight line movement

4
tion, and electric switch means connected to said operating lever.

in parallel relation with the direction of movement of the armature 10. A helical tension spring 27 biases the rack 28 to its uppermost position with the armature in its lowermost position as shown in Fig. 1. This spring extends through a longitudinal slot 28 in the bar portion 24 and has its upper end secured to a pin 29 mounted on the support 7 and its lower end secured to a pin 30 mounted on the lower end of the bar portion 24. It will be observed that this spring 27 is the means for biasing the operating lever 5 to its open circuit position.

As shown, the bridging contact 4 is mounted on a spring strap 31 which extends through a slot 32 in a projection 33 on the upper end of the lever 5 and downward lengthwise of the lever to a point adjacent the lower end of the lever where the strap is provided with a right-angle projection 34 engaging the lever. By means of a screw 35 extending through the strap, the strap may be given a curvature or bias between the points 33 and 34, thereby to adjust the spacing between the bridging member 4 and the stationary contacts when the contactor is in its open circuit position and the amount of wipe between the bridging member and the stationary contacts.

While I have shown a particular embodiment of my invention, it will be understood, of course, that I do not wish to be limited thereto since many modifications may be made and I therefore contemplate by the appended claims to cover any such modifications as fall within the true spirit and scope of my invention.

What I claim as new and desire to secure by Letters Patent of the United States is:

1. A shockproof electric switch comprising a support, a magnet frame fixed to said support, a coil on said frame, a plunger armature for said coil mounted for movement in a substantially vertical direction between attracted and unattracted positions, a first movable rack fixed to said armature for movement therewith, a pinion engaged by said rack, a crank connected to said pinion moved by said armature from one dead center position to another, a second movable rack slidably mounted on said support and engaging said pinion on its side opposite said first rack, said second rack being mounted for movement in a direction substantially parallel to the direction of movement of said first rack and having a weight counterbalancing the weight of said armature and said first rack, a switch operating lever, a link connecting said crank with said lever so as to move said lever between closed and open circuit positions upon rotation of said crank substantially between its said dead center positions, a spring connected to said second rack for biasing said armature to its unattracted posi-

2. A shockproof electric switch comprising a support, a first movable rack slidably mounted on said support, actuating means connected to drive said first rack, a pinion rotatably mounted on said support and engaging said first rack to be driven thereby, a crank connected to said pinion and movable through at least 180° from one dead center position to another, a second movable rack slidably mounted on said support and engaging said pinion on the side opposite said first movable rack, the weight of said second rack counterbalancing the weight of said first rack, a movable switch member, and a link connecting said crank with said switch member to move said switch member between closed and open circuit positions each corresponding to one of said dead center positions.

3. A shockproof electric switch comprising a support, a first movable rack slidably mounted on said support for movement in a substantially vertical direction, actuating means connected to drive said first rack, a pinion rotatably mounted on said support and engaging said first rack to be driven thereby, a crank connected to said pinion and movable thereby through at least 180° from one dead center position to another, a second movable rack slidably mounted on said support for movement substantially parallel to the direction of movement of said first rack and engaging said pinion on the side opposite said first rack, the weight of said second rack counterbalancing the weight of said first rack, a movable switch member, and a link connecting said crank with said switch member to move said switch member between open and closed circuit positions upon rotation of said crank substantially between its said dead center positions.
